UNITED STATES PATENT OFFICE.

ERNEST STUART DANIELS, OF WASHINGTON, DISTRICT OF COLUMBIA, AND HAROLD PITMAN SCHUCK, OF EAST ORANGE, NEW JERSEY.

PARQUET FLOORING AND WALL PANELING.

Application filed October 16, 1923. Serial No. 668,907.

To all whom it may concern:

Be it known that we, ERNEST STUART DANIELS, a subject of the King of England, and HAROLD PITMAN SCHUCK, a citizen of the United States, residing, respectively, at Washington, District of Columbia, and at East Orange, in the county of Essex and State of New Jersey, have invented certain new and useful Improvements in Parquet 5 Floorings and Wall Panelings; and we do hereby declare the following to be a full, clear, and exact description of the invention, such as will enable others skilled in the art to which it appertains to make and use the 10 same.

This invention relates to flooring, and more particularly to what is commonly known as parquet flooring.

The primary object of the invention is to provide flooring material constructed in sections having means rigid therewith for securing together, by interlocking tongue and groove connections, a group or multiplicity of sections in properly assembled relation 20 to form a floor, without other fastening means than said interlocking connections.

A further object is to provide flooring material of the character referred to, adapted for use in constructing wall panels 30 or paneled ceilings and the like.

The invention will first be hereinafter more particularly described, with reference to the accompanying drawings, which are to be taken as a part of this specification, and 35 then pointed out in the claims at the end of the description.

In said drawings, Fig. 1 is a plan view, partly in section of a portion of a parquet floor embodying our invention; one section 40 being shown detached, partly in plan and partly in sectional view, in position for assembling or uniting the same with two adjoining sections at one corner of the group;

Fig. 2 is a perspective view of a group of 45 four sections of flooring material embodying our invention arranged in proper relation for assembling the group or a multiplicity of sections;

Fig. 3 is a perspective view of a portion 50 of a wall panel or paneled ceiling composed of a group of sections of flooring material embodying our invention; and

Fig. 4 is a perspective view of one of the 55 sections shown in Fig. 3 detached; the near edge thereof being shown in section.

Referring to said drawings, in which the same reference characters are used to denote corresponding parts in different views, the letters A, A, in Figs. 1 and 2, denote composite sections of flooring material constructed in accordance with our invention, and consisting, as shown, of planks or boards secured together edge to edge with the grain of the wood in each section running substantially at right angles to the running of the grain in any adjoining section so as to form practically an integral section of flooring so constructed as to adapt a multiplicity of such sections to be assembled and rigidly secured together in such manner as to form a floor or wall panel without the use of nails, screws or other fastening means than the interlocking tongues and grooves with which the sections are provided. The sections may be of any desired form and size, either 60 square or rectangular or octagonal, and any suitable material may be used to form the individual sections, either solid or composite. Preferably the sections consist of a number of boards or blocks of wood placed edge to edge and provided along the outer edges of the section with longitudinal grooves a, while the end portions thereof are provided with transverse grooves in which are secured strips b of wood, which are a little shorter 65 than the length of the groove so as to provide projecting tongues at opposite ends of the section adapted to fit snugly within the longitudinal grooves of adjoining sections with the ends of the tongues flush with the 70 bottoms of said longitudinal grooves, and secure the assembled sections together, in the manner indicated in the drawings, so that when a group or multiplicity of sections are assembled in proper relation the entire 75 group will be held together by the interlocking tongues and grooves without other fastening means. If desired, fastening strips overlying the edges of the assembled sections may be used, for greater security and 80 to impart a more finished appearance to the floor as a whole as shown at a¹, Fig. 1.

In Figs. 3 and 4 we have shown a group of sections A¹ of flooring material somewhat larger than the sections shown in Figs. 1 and 2, which are used to form a wall panel, or the like, with the sections assembled in a vertical position, instead of a horizontal position, in which case it may be desirable to secure a fastening strip or board over the 100 105 110

meeting edges of the assembled sections and extending the entire length of the group, as indicated by the dotted lines a^2 , Fig 3. The sections of flooring material may be constructed in different sizes, according to the wishes of the manufacturer or user, or to meet different requirements in practical use. For example, it is desirable that the sections used for the purpose of a parquet floor should be of smaller size than those used for a wall panel or a paneled ceiling. The sections are preferably constructed of a series of short and narrow boards having smooth adjoining edges and secured together edge to edge, in the manner indicated in the drawings, but if desired, the series of boards may be secured together by tongue and groove connections in addition to the transverse strips.

It will be observed that the longitudinal grooves extend along the edges of the section parallel with the grain of the wood, substantially at right angles to the transverse grooves which extend substantially at right angles to the grain of the wood, and that the strips fitted in said transverse grooves extend at an angle to the grain of the wood, thus producing a very substantial, strong and durable section of flooring material having a neat and finished appearance and adapted for various uses to which flooring material of the character described may be put.

We desire it to be understood that the word "flooring" as used in the appended claims is intended to include not only flooring material but wall panels and paneled ceilings and various other structures in which our invention may be used. Furthermore, in the broader aspects of the invention, for some purposes, other material than wood may be used to form similarly tongued and grooved flooring sections adapted to perform to a greater or less degree substantially the same function as sections composed entirely of wood, and therefore we do not desire to limit our invention to parquet flooring or wall panels made entirely of wood, though wood is desirable and preferable, and in some cases indispensable to produce the best results.

By the described construction we are enabled to produce at comparatively little expense a nicely finished and durable flooring material, by the utilization of the heretofore unused and waste products of lumber, such as short pieces of flooring material, which are usually cast off and used as fire wood, and more particularly the utilization of hard but inexpensive wood, such as gum lumber, which is unfit for use as ordinary flooring material, because of its natural tendency to warp and split, and which, for this reason, is sold at a very low price as compared with ordinary flooring material. Furthermore,

the described reinforcement of the composite sections by means of the transverse strips or tie-pieces inserted in grooves at opposite ends of a section serves to bind the several elements of the section firmly together in such manner as to prevent warping and splitting and to form a practically integral structure with the grain of the wood in the major part of the section running at an angle, preferably substantially at right angles, to the grain of the wood in said strips or tie-pieces.

Having thus described our invention, what we claim as new and desire to secure by Letters Patent of the United States is:

1. A parquet flooring comprising individually formed sections of flooring material interlocked and held together in assembled relation by interlocking longitudinal and transverse tongue and groove connections between the sections; the longitudinal grooves extending along opposite edges of the section at an angle to the tongues; the individual sections being composed of short pieces of boards secured together edge to edge by tongues fitting in registering grooves in the ends of the respective boards; the ends of the tongues terminating flush with the bottoms of the longitudinal grooves.

2. A parquet flooring comprising individually formed sections of flooring material compositely held together by transverse tongues, the several sections being held in assembled relation by longitudinal and transverse tongue and groove connections extending along the edges of adjacent sections, each individual section consisting of a plurality of boards joined together edge to edge by the tongues fitting into said grooves with the grain of the wood in one section running substantially at right angles to the grain of the wood in adjoining sections.

3. A parquet flooring composed of substantially square sections of flooring material interlocked and held together in assembled relation by longitudinal and transverse tongue and groove connections extending along the edges of adjacent sections, the individual sections consisting of a plurality of boards joined together edge to edge with the grain of the wood in one section running substantially at right angles to the grain of the wood in adjoining sections; said boards being secured together by strips of wood fitted in said transverse grooves at an angle to the grain of the wood so as to form projecting tongues at opposite ends of the boards adapted to enter the longitudinal grooves of adjacent sections and secure the assembled sections together.

4. Parquet flooring sections composed of wooden pieces having transverse grooves in opposite ends thereof running at an angle to the grain of the wood and longitudinal grooves in the edges thereof running paral-

lel with the grain of the wood, and strips of wood inserted and fixed in said transverse grooves with the outer edges thereof protruding so as to form tongues for insertion in the longitudinal grooves of adjacent sections similarly constructed and assembled to form a floor or wall panel, the assembled sections being individually and compositely held in properly assembled relation by said 10 tongues and grooves without other fastening means.

5. A parquet flooring section composed of wooden pieces having transverse grooves in opposite ends thereof running at an angle 15 to the grain of the wood and longitudinal grooves in the edges thereof running parallel with the grain of the wood, and strips of wood inserted and fixed in said transverse grooves with the outer edges thereof protruding so as to form tongues for insertion 20 in the longitudinal grooves of adjacent sections similarly constructed and assembled to form a floor or wall panel, the assembled sections being held in properly assembled 25 relation by said tongues and grooves without other fastening means; the grain of the wood in each section running at an angle to the grain of the wood in adjacent sections.

6. A parquet flooring section consisting 30 of several boards or blocks of wood placed edge to edge and having transverse registering grooves in opposite ends thereof and longitudinal grooves in the outer edges of the outer boards; said boards being secured 35 together by strips of wood inserted and

fixed in said transverse grooves, the said strips protruding beyond the ends of the boards so as to form tongues for insertion in the longitudinal grooves of adjacent sections, whereby similarly constructed sections may be assembled to form a floor or 40 wall panel and secured together by said tongues and grooves without other fastening means.

7. A parquet flooring section consisting 45 of several boards or blocks of wood placed edge to edge and having transverse registering grooves in opposite ends thereof and longitudinal grooves in the outer edges of the outer boards; said boards being secured 50 together by strips of wood inserted and fixed in said transverse grooves, the said strips protruding beyond the ends of the boards so as to form tongues for insertion in the longitudinal grooves of adjacent sections, whereby similarly constructed sections may be assembled to form a floor or 55 wall panel and secured together by said tongues and grooves without other fastening means; the grain of the wood in said 60 strips running at an angle to the grain of the wood in said boards, and the grain of the wood in each of the assembled sections being adapted to run at an angle to the grain of the wood in adjacent sections. 65

In testimony whereof we affix our signatures.

ERNEST STUART DANIELS.
HAROLD PITMAN SCHUCK.
